United States Patent Office

Des. 179,732
Patented Feb. 19, 1957

179,732

SNAP FASTENER

Frank J. Kahl, Los Angeles, and Elbert M. Coplen,
Venice, Calif.

Application June 6, 1955, Serial No. 36,382

Term of patent 14 years

(Cl. D17—14)

Fig. 1

Fig. 2

Fig. 3

Figure 1 is a side elevational view of a snap fastener, showing our new design;

Figure 2 is an end view thereof in the direction of the arrows 2—2 in Figure 1; and

Figure 3 is a top plan view in the direction of the arrows 3—3 in Figure 1.

The dominant features of our new design are shown in solid lines in the drawing, the dotted line showing of the tailpiece being omitted in Figure 2 for convenience in illustration.

We claim:

The ornamental design for a snap fastener, as shown and described.
